[57] CLAIM

The ornamental design for a raised curb marker or similar article, substantially as shown.

DESCRIPTION

FIG. 1 is a front perspective view of a raised curb marker or similar article embodying my new design;
FIG. 2 is a top plan view thereof;
FIG. 3 is a front elevational view thereof;
FIG. 4 is a rear elevational view thereof;
FIG. 5 is a side elevational view thereof; and
FIG. 6 is a bottom view thereof.

Fig. 5
